UNITED STATES PATENT OFFICE.

ABRAM REESE, OF PITTSBURG, PENNSYLVANIA, ASSIGNOR TO THE REESE SAFETY BRAKE COMPANY, (LIMITED,) OF SAME PLACE.

CAR-BRAKE.

SPECIFICATION forming part of Letters Patent No. 377,438, dated February 7, 1888.

Application filed May 12, 1887. Serial No. 237,938. (No model.)

To all whom it may concern:

Be it known that I, ABRAM REESE, of Pittsburgh, in the county of Allegheny and State of Pennsylvania, have invented a new and useful 5 Improvement in Car-Brakes; and I do hereby declare the following to be a full, clear, and exact description thereof.

My invention relates to car-brakes, and more especially to that class of brakes in which the 10 brake is applied by the impact of one car on another.

In an application filed of even date herewith I have described a brake which consists, generally, in backing the draw-head with two 15 springs, one of which is longer than the other, and bears against the draw-head, so as to permit a certain amount of movement of the draw-head and draw-bar before it is necessary to compress both springs. In the rear of the 20 draw-bar is the brake-operating lever, an intervening space, which is taken up by a filling-block, existing between this lever and the end of the draw-bar, so that by removing or raising this filling-block the draw-bar can move back- 25 ward without applying the brakes. My present invention relates to a modification of the filling-block used in this brake; and to that end it consists, generally, in interposing between the end of the draw-bar and a pivoted 30 brake-lever a sliding rocking dog or block, which when in one position transmits the thrust of the draw-bar to the brake-lever, and in the other permits the backward play of the draw-bar without affecting the brakes; and the 35 invention also consists in a spring-backed draw-head having a draw-bar attached thereto, a rocking sliding block in the rear of said draw-bar and in line therewith, and a brake-operating lever connected to the brakes in the rear 40 of said rocking block, and against which it impinges, whereby the thrust on the draw-head can be transmitted to the brake when desired.

The invention also consists in certain other improvements, all of which will be more fully 45 hereinafter set forth.

To enable others skilled in the art to make and use my invention, I will describe the same, referring to the accompanying drawings, in which—

50 Figure 1 is a plan view of the bottom of one

end of a car with my improved brake applied thereto. Fig. 2 is a detail view. Fig. 3 is a section on the line *x-x*, Fig. 1; and Fig. 4 is a central horizontal section.

Like letters refer to like parts in each of the 55 figures of the drawings.

The draw-head *a* slides in suitable guides in the end of the car-frame *b*, and has attached thereto the draw-bar or extension-rod *c*, which extends through openings in the front and rear 60 follower-plates, *d e*, and in the rear of the latter carries a pin or key, *f*, which throws the strain on the follower-plate when the pull comes on the draw-bar. Interposed between these front and rear follower-plates, and bearing against 65 them at its ends, is the outer coiled spring, *g*, and inside of this spring is an inner coiled spring, *h*, which bears at one end against the rear follower-plate and at its other extends through an enlarged hole in the front follower-plate until it bears against the rear end of the 70 draw-head *a*, this spring being longer, preferably about one inch, than the outer spring, so that the draw-head can move back a certain distance without the necessity of exerting 75 power to compress both springs. In the rear of the draw-bar is the rocking block *i*, which is provided on each side with a stud, *j*, Fig. 3, which slides in a slot, *k*, formed in each side of a supporting-piece, *l*, attached to the under 80 side of the car-frame, this rocking block having a downwardly-extending arm, *m*, which is connected by a link, *n*, and yielding connection *n'* to a rock-arm, *o*, secured to a rock-shaft, *o'*, which in turn is provided with a rock-arm, *p*, 85 operated by a rod, *q*, which extends to the top of the car-body, where it is accessible. The yielding connection *n'*, which consists of two springs—one on each side of the arm *o*—takes up any sudden thrust or strain which may be 90 thrown on the rocking block *i*, and thus prevents the breaking of parts. To prevent the rocking block *i* from coming out of the supporting-piece *l*, a rod or pin, *m'*, is inserted across the opening in the support-piece in front 95 of the arm *m*, in which the block is placed. Pivoted to the supporting-piece *l* is the brake-operating lever *r*, one end of which is directly in the line of movement of the block *i*, so that as the latter is moved back by the backward 100

movement of the draw-bar it will rock the 5
brake-lever, and through the intervening
connections between the latter and the brakes
apply them. The connecting rods and levers used
to connect the brake-operating lever with the
brakes are the same as those now in use, and
therefore no detail description of them will be
given.

The operation of the device is as follows:
10 If the preceding car or locomotive should be
brought to a stop or slowed up, its impact on
the draw-head *a* will cause the latter to com-
press the inner spring until the draw-head
strikes the front follower-plate, when any fur-
ther movement is resisted by both springs.
15 During this backward movement of the draw-
head and draw-bar, if the block *i* is directly in
line with the end of the latter, the block will
be forced backward and carry with it the end
20 of the brake-operating lever *r*, so that the
brakes are applied to the wheels. If, however,
the rod *q* is moved so as to rock the block *i* on
its pivot or studs upward, a sufficient space will
25 be left below the block for the draw-bar to re-
cede in without affecting the brake-lever, and
the brakes will not be applied by any impact
on the draw-head.

Having now described my invention, what
I claim is—

1. In a car-brake, the combination of a 30
spring-backed draw-head having a draw-bar
or extension-rod attached thereto, a brake-op-
erating lever in the rear of said draw-bar, and
a sliding rocking filling-block between said
brake-operating lever and the draw-bar and in-
dependent thereof, substantially as described. 35

2. In a car-brake, the combination of a
draw-head having an extension-rod or draw-
bar attached thereto, a brake-operating lever
in the rear of said draw-bar, a sliding rocking 40
filling-block between said draw-bar and oper-
ating-lever and independent thereof, and
means for rocking said block, substantially as
described.

3. In a car-brake, the combination of the 45
draw-head having a draw-bar attached thereto,
a sliding rocking block, *i*, having the down-
ward-extending arm *m*, a brake-operating le-
ver, *r*, and means connected to said arm *m* for
rocking said block, substantially as and for the 50
purposes set forth.

In testimony whereof I, the said ABRAM
REESE, have hereunto set my hand.

ABRAM REESE.
